UNITED STATES PATENT OFFICE.

MARTIN W. CARR, OF SOMERVILLE, MASSACHUSETTS.

DESIGN FOR A VASE.

SPECIFICATION forming part of Design No. 16,542, dated February 23, 1886.

Application filed October 22, 1885. Serial No. 180,679. Term of patent 3½ years.

To all whom it may concern:

Be it known that I, MARTIN W. CARR, of Somerville, in the county Middlesex, State of Massachusetts, have invented and produced a new and original Design for Vases, of which the following is a full, clear, and exact description, reference being had to the accompanying drawing, forming a part of this specification, and which shows the vase in isometrical perspective.

This design comprises three crossed standards, C C' C'', which represent the stems of the cat-tail plant, and which are provided at their upper ends with cylindrical enlargements representing cat-tail spikes. These standards cross each other at a point above the center of their length, and stand approximately at equal distances apart, being divergent in opposite directions from their point of intersection D. A dish-shaped vase, A, is disposed centrally between the standards below their point of

intersection, and chains B extend from points equidistant on the rim of said vase in converging lines to the point of intersection of the standards.

25

I claim—

The design for a vase herein shown and described, said design consisting of crossing standards representing stems of the cat-tail plant, said stems being divergent both upward 30 and downward from their point of intersection, and provided at their upper ends with cylindrical enlargements representing cat-tail spikes, a vase disposed between said standards below their point of intersection, and 35 chains converging from said vase to the point of intersection.

MARTIN W. CARR.
